INERTIA BUFFER

Paul H. Dixon, Rockford, Ill., assignor to United Shoe Machinery Corporation, Flemington, N.J., a corporation of New Jersey

Application November 14, 1946, Serial No. 709,709

9 Claims. (Cl. 188—1)

1

This invention relates to energy dissipating buffers for reducing the speed of heavy, fast moving objects and is illustrated as embodied in an automatic 37 mm. cannon such as is fully disclosed in an application Serial No. 721,058 filed January 9, 1947 in my name.

In order to increase the cyclic rate of 37 mm. cannon for example, for use in airplanes, it is necessary to increase the speed, in recoil and counter-recoil, of the bolt assembly of such cannon to a point which makes it necessary to check the speed of said assembly near the end of its movement in counter-recoil in order to insure against breakage of parts and to insure the proper locking of the bolt assembly in battery position.

With the foregoing consideration in view it is an object of the present invention to provide a buffer, two of which may be advantageously used for quickly and effectively reducing the speed of the bolt assembly of the above-mentioned cannon during its movement in counter-recoil.

In the illustrative construction, each of the buffers is operatively connected through a latch to a slider, which forms part of the bolt assembly, near the forward end of the counter-recoil movement of said slider, the latch being disconnected from the slider before said slider reaches its battery position, the arrangement being such that when the slider is disconnected it still has sufficient speed to cause a bolt forming part of said assembly to be moved to its locked position.

The various features of the invention as defined in the accompanying claims will be understood and appreciated from the following detailed description read in connection with the accompanying drawings in which,

Fig. 1 is a perspective view showing one of a pair of buffers incorporated in the gun in said application Serial No. 721,058;

Fig. 2 is a side view, partly broken away and partly in section, illustrating the buffer of Fig. 1 at the time it is first engaged by a slide of a bolt assembly of the gun;

Fig. 3 is a view similar to Fig. 2 but showing the buffer after it has been released by the slider but is held in its forward position by said slider;

Fig. 4 is an exploded view showing in perspective the various parts of the buffer;

Fig. 5 is a section on line V—V of Fig. 3;

Figs. 6, 7 and 8 are views on line VI—VI of Fig. 5 showing the relation of a cage and inertia block of the buffer during different stages of the checking action of said buffer, and

Fig. 9 is a view on line VI—VI of Fig. 5 showing

2

opposing portions of a slightly modified cage and inertia block.

Each of the illustrative buffers of the gun above referred to comprises a cage or slide 30 which is provided with inturned flanges 32 (Figs. 1, 4, 5 and 6), 33 (Figs. 4 and 6) fitting in channel guides 34, 35 respectively formed in a rail 36 secured by a bolt 40 to a barrel extension 42 (Figs. 1, 2 and 3) of the gun, a lug 44, which is formed integral with the rail and engages in a longitudinal guideway 48, (Figs. 1, 3, 4 and 5) of the cage, cooperating with the channels 34, 35 in guiding said cage in a rectilinear longitudinal path extending lengthwise of the gun or parallel to the path of movement in recoil and counter-recoil of a slider 52 (Fig. 1) forming part of a bolt assembly 53 of the gun. Formed integral with the rail 36 is a lug 46 (Figs. 2, 3, 4 and 6) the purpose of which will appear later.

Arranged at opposite sides of a chamber, which is formed by the rail 36 and a channel or recess 54 of the cage 30, are rows of series of V-shaped teeth 56, 56a (Figs. 6 and 7) constituting racks 58, 58a which face each other and extend lengthwise of the path of movement of the cage, front and rear operating faces 60, 62, 60a, 62a of the teeth 56, 56a respectively being disposed at 45° to said path and the teeth of the rack at one side of the channel being offset longitudinally by one-half a tooth from the teeth of the rack at the other side of the channel. Mounted for transverse or lateral movement in the channel 54 of the cage 30 with its rear and forward ends in sliding engagement with faces 64 (Figs. 4, 6, 7, 8 and 9), 66 (Figs. 2, 4 and 6) of the lugs 44, 46 respectively, is an inertia block 68 having at its upper and lower faces rows or series of V-shaped teeth 70 (Figs. 6 and 7), 70a which are similar to the teeth of the racks 58, 58a of the cage 30 and form racks 72, 72a (Figs. 4, 6 and 7) which face away from each other and are arranged in opposed and inter-engaging relation with the racks 58, 58a of the cage. The inertia block 68 may be defined as movable in a path transverse to the path of movement of the slide 30.

It will be noted that the teeth 70, 70a of the inertia block 68 are in transverse alinement or register, the distance 74 (Figs. 6 and 7) between the ends of the opposite or aligned teeth of said block being slightly less than the transverse distance 76 between opposite portions of the teeth 56, 56a of the racks 58, 58a on any straight line normal to the path of movement of the cage, it being apparent that since the teeth 56, 56a of

said racks are offset lengthwise by one-half a tooth the zig-zag channel 54 is of uniform width. With the above construction clearances 77 (Figs. 6 and 7) are formed between opposing racks 58, 72 and 58a, 72a.

As will be explained later, as the cage 30 is moved forward, that is, in the direction indicated by arrow 78, at a high rate of speed in response to counter-recoil action of the slider 52, the operating or leading faces 69 of the teeth 56 of the rack 58 are slammed, for example, as illustrated in Fig. 6, against the rear faces 80 (Figs. 6 and 7) of the teeth 70 of rack 72 of the inertia block 68, with the result that said block is moved transversely, that is, in the direction indicated by arrow 81, causing the faces 82a of the teeth 70a to collide with rear faces 62a of the teeth 56a as illustrated in Fig. 7, the leading faces 60a of the teeth 56a of the rack 58a thereafter engaging the faces 80a of the teeth 70a of the block 68 and thus causing faces 82 of the teeth 70 of the block to move transversely in an opposite direction against the rear faces 62 of the teeth 56 of the rack 58, the oncoming leading faces 60 of the teeth 56 then striking the rear faces 80 of the teeth 70 of the rack 58 to repeat the above-described cycle of operation.

The channel 54, which extends lengthwise of the path of longitudinal movement of the cage or slide 30, may be described as having serrated edges or opposite sides bounded by teeth arranged in series or the form of racks extending lengthwise of said path. Moreover, it will be understood that since the teeth 56, 56a, 70, 70a may deviate from the form shown in Figs. 6, 7 and 8 and have their ends and roots rounded off, for example as illustrated in Fig. 9, the edges of the channel 54 may be defined as sinuous or undulatory. In fact, sharp teeth of the buffer will become somewhat rounded after being used for a short time.

The inertia block 68 which is confined in the channel 54 of the cage 30 has its teeth 70, 70a arranged in series extending lengthwise of the path of movement of the cage, as above explained, the teeth 70 at one side of the block being positioned in transverse alinement or register with the teeth 70a at the other side of the block. Since the ends of the teeth or serrations of the block 68 may be initially rounded somewhat as illustrated in Fig. 9, or may become rounded in use, the block 68 may also be defined as having undulatory or sinuous edges and as being alternately wide and narrow, and wide portions of the block or the distance 74 between the points or outer ends of the teeth 70, 70a of the block 68 being slightly less than the width 76 of the channel 54. Furthermore, the cage or slide 30 may be described as having formed between its opposite racks or sinuous edges, a longitudinally clear space, that is, a space which is clear in the direction of movement of the slide. The clear space which has a width represented by reference numeral 83 is slightly wider than the distance 85 between the roots of opposing teeth 70, 70a of the block 68 plus the height of one of the teeth of said block.

The cage or slide 30 may also be described as having longitudinally arranged serrations, rows of teeth 56, 56a or sinuous edges which are in inter-engaging relation with longitudinally arranged serrations, rows of teeth 70, 70a or sinuous edges of the block 68, the serrations, teeth or sinuous edges of one of said members overlapping transversely the opposing teeth, serra-

tions or sinuous edges of the other member. The teeth 56, 56a of the serrated or toothed edges of the cage 30 or the projecting portions of the opposite sinuous edges of the cage may be described as being off-set one-half a tooth or half a projecting portion longitudinally from one another and as facing inwardly, that is toward one another, the teeth 70, 70a of the serrated or toothed edges or the projecting portions of the sinuous edges of the block 68 being described as being in transverse alinement with each other and as facing outwardly, that is away from each other.

The cage 30 has pivotally connected to it by a pin 86 (Figs. 1 to 4) a latch 88 having a face 90 (Figs. 2 and 3) which, when the buffer is in a retracted position with the latch in coupling position in engagement with a stop 92 (Fig. 1) rests on top of a lug 94 of the rail 36. The cage 30 is held in its retracted position by a spring 96 encircling a rod 98 which slides through bores 100 (Fig. 3) in depending lugs 102, 104 of the cage, has a shoulder 106 (Figs. 3 and 4) engaged by one end of the spring and is in engagement with the barrel extension 42, the other end of the spring engaging the lug 102 of the cage.

As the slider 52, actuated by a reaction unit (not shown), moves in counter-recoil at a high speed, an abutment 108 formed integral with the slider engages a shoulder 110 of the latch 88, the face 90 of which at that time is sustained by the lug 94 of the rail 36, causing the cage 30 to be moved forward until said face has been moved to its position shown in Fig. 3, thereby permitting the latch to swing downward and the shoulder 110, which is arranged higher than the pin 86, to be lowered below the abutment 108. As the abutment 108 leaves the shoulder 110 it slides over an upper face of the latch 88 and in its battery position is still in contact with said face causing a face 112 (Fig. 2) of the latch to be held in contact with a bevel face 114 (Figs. 2 and 3) of the lug 94, for the purpose of retaining the cage 30 in its forward position until such time as the abutment 108 of the slide 52 has moved rearward in recoil away from the latch, the spring 96 thereafter operating to move the cage upon the rail 36 back to its rearward position in which the latch 88 is in engagement with the stop 92.

In the illustrative embodiment the inertia block 68 has twelve teeth at each of its upper and its lower edges, the teeth at each edge being constructed and arranged to engage opposing teeth of the cage. By providing a plurality of colliding surfaces the impact load is well distributed thus insuring that the various parts stand up effectively under considerable use.

By causing a plurality of collisions between the teeth of the cage 30 and the teeth of the inertia block 68 a large amount of energy is quickly and effectively dissipated, resulting in the intermittent slowing down of the cage by the block. It will be apparent that the intermittent slowing down of the cage 30 results in a series of collisions between the latch 30 and the abutment 108 of the slider 52 and this, together with various friction losses between the parts, adds materially to the dissipation of the energy of the counter-recoiling slider.

The rate of dissipation of energy will vary approximately in accordance with the square of the velocity of the moving parts, the restitution factor of steel being such that the velocity of the slider is materially checked after the teeth of the cage 30 have moved past a few teeth of the inertia block 68. As the high velocity is materially re-

duced the percentage of total kinetic energy absorbed per unit of movement of the cage 30 is greatly reduced and accordingly the cage may move a considerable distance without depriving the slide of a highly desirable residual speed necessary to cause said slide to lock a bolt associated with it in battery position. In order, however, to insure that there shall not be any drag whatsoever on the slider 52 after its speed has been reduced to a value sufficiently low to effect the proper locking of the bolt assembly parts, the latch 88 is cammed down out of driving relation with the abutment 108 of the slider 52 at a predetermined time, depending upon the position of the lug 94.

Although the buffer has been illustrated with reference to the above-mentioned gun it will be understood that such a buffer may be effectively used wherever it is desired suddenly to reduce the speed of fast moving parts.

Having thus described my invention, what I claim as new and desire to secure by Letters Patent of the United States is:

1. In a buffer, two members, one movable in a predetermined path and the other movable in a path transverse to said path, means for constraining said members for movement in said paths, each of said members having two series of serrations which extend generally lengthwise of said predetermined path and are positioned in opposed relation to the serrations, respectively, of the other member, the serrations of one of the members overlapping the serrations of the other of said members lengthwise of said transverse path and being so constructed and arranged that movement of said one member in said predetermined path will cause movement of the other member in said transverse path.

2. In a buffer, a slide movable in a fixed path, said slide having a channel which extends generally lengthwise of said path and which is of uniform width and has sinuous edges, an inertia block which is arranged in said channel and is constrained for movement in a path disposed at a substantial angle to said path, and means for constraining said slide and block for movement in said paths, said block having sinuous edges and being alternately wider and narrower in width, the wider portions of the block being slightly less than the width of the channel.

3. In a buffer, a slide which is movable in a predetermined path and has a pair of spaced racks extending lengthwise of said path and facing toward each other, teeth of one of said racks being offset lengthwise of said path from the teeth of the other, an inertia block which is movable in a path disposed transversely of said predetermined path and which is arranged in the slide and has a pair of racks facing away from each other, teeth of the racks of said block being positioned adjacent to the teeth of the racks of the slide and being in alignment lengthwise of said predetermined path, means for constraining said slide and block for movement in said paths, and means for causing the slide to be moved in said predetermined path at a high rate of speed, said racks of the slide and the block being so constructed and arranged that the racks of the inertia block are moved into colliding relation with opposed racks of the slide in response to movement of the slide in said predetermined path.

4. In a buffer, a slide which is movable in a predetermined path and has spaced racks extending lengthwise of said path and facing toward

each other, teeth of one of said racks being staggered lengthwise of said path with relation to the teeth of the other rack, an inertia block movable in a path extending transversely of said predetermined path and having racks facing away from each other, teeth of the racks of the block being similar to the teeth of the racks of the slide and being arranged in alignment lengthwise of said predetermined path, and means for constraining said slide and block for movement in said paths, said slide having formed between its racks a clear space which extends lengthwise of said predetermined path and which is slightly wider than the distance between the roots of opposing teeth of the inertia block plus the height of one of the teeth of said block.

5. In a buffer, a slide, an inertia block, means for constraining the slide and the block for movement in paths disposed at right angles to each other, said block and said slide having pairs of opposed interengaging racks, teeth of which are similar, the teeth of each of the racks of the slide being arranged in a series extending lengthwise of the path of movement of the slide and being offset lengthwise of said path from the teeth of the other rack, the teeth of the racks of the block being arranged in two series disposed lengthwise of the path of movement of the slide, the teeth of one of the racks of said block being arranged in alignment lengthwise of the path of movement of the slide with the teeth of the other rack of said block, the distance between the ends of the aligned teeth of the block being slightly less than the distance between opposite portions of the racks of the slide.

6. In a buffer, a guide, a cage movable in a predetermined path on the guide, said cage having a recess provided with opposite sides which extend generally lengthwise of said path and are serrated, the serrations at one side of said recess being offset lengthwise of said path from the serrations at the other side of the recess, and an inertia block which is positioned in the recess and has serrated opposite sides, serrations at opposite sides of the block being arranged in substantial alignment lengthwise of said path and being constructed and arranged to interengage the serrations at opposite sides of said recess, the construction and arrangement being such that movement of the cage in said path effects movement of the block transversely of said path, whereby the block is moved into colliding engagement with the cage to check movement of said cage and to absorb energy to slow down movement of said cage.

7. In a buffer, a cage movable in a predetermined path and having spaced rows of teeth which are parallel to each other and to said path and which face each other, the teeth of one row being similar to the teeth of the other row and being offset lengthwise of said path a half a tooth with relation to opposing teeth of the other row, an inertia block which is movable in a path transverse to said predetermined path and which has parallel rows of teeth which face away from each other and are similar to the teeth of the cage and which are arranged in alignment with each other, the distance between opposing points on the opposite teeth of the cage being slightly greater than the distance between the ends of opposing teeth of the block, a latch connected to the cage, means for holding the latch in a coupling position, and a heavy high speed member, the speed of which is to be reduced, constructed and arranged to engage said latch in its coupling position to move

the cage in said predetermined path, thereby causing the block to move transversely by hammering action of the teeth of the cage against the teeth on the block, with the result that movement of the cage is resisted and energy is dissipated by the interaction between the various parts to reduce the speed of said high speed member.

8. In a buffer, a slide constrained for movement in a rectilinear path, an inertia block constrained for movement in a path disposed transversely of said rectilinear path, means for constraining the slide and the block for movement in their respective paths, said slide and said block each having a pair of racks extending generally lengthwise of said rectilinear path, the racks on the slide being arranged in opposed relation to the racks of the block, the teeth of one of the racks of the slide being offset lengthwise of said rectilinear path from the teeth of the other rack of the slide and the teeth of the racks of the block being in transverse alinement with each other, opposed teeth of the slide and the block being constructed and arranged to interengage as the slide is moved in said rectilinear path, a heavy high speed member, and means for operatively connecting the slide to said member to effect movement of the slide in said rectilinear path and movement of the block in said transverse path to cause collisions between teeth of the slide and the block and accordingly dissipation of energy to check movement of the slide acted upon by said member in said rectilinear path.

9. In a buffer, a slide constrained for movement in a rectilinear path, means for imparting energy to be dissipated to the slide, said slide being pro-

vided with a channel opposite sides of which are formed by racks extending generally lengthwise of said path, teeth of one of said racks being offset lengthwise of said path with relation to teeth of the other of said racks, an inertia block which is arranged in said channel and is constrained for movement in a transverse path at right angles to said rectilinear path, means for constraining said slide and said block for movement in their respective paths, said block having opposite sides which are in opposed relation to the racks respectively of the slide and which are formed by racks teeth of which are similar to each other and to the teeth of the racks of the slide, said block being movable in said transverse path in response to movement of the slide in said longitudinal path to cause the teeth at opposite sides of the block to collide with teeth of the racks at opposite sides of the channel intermittently to check movement of the slide and to cause energy imparted to the slide to be dissipated.
